FOUNTAIN PEN

Karl Y. Johannesson, Berwick, Pa.

Original application July 20, 1933, Serial No. 681,265. Divided and this application July 19, 1935, Serial No. 32,143

13 Claims. (Cl. 120—48)

This invention relates generally to fountain pens and has particular reference to pens of the sackless type, and is a division of my co-pending application Serial No. 681,265, filed July 20, 1933 for Fountain pen desk set, now Patent 2,011,639 granted August 20, 1935.

One object of the invention is the provision of a fountain pen which may be filled by forcing the ink into the reservoir.

Another object of the invention is the provision of a fountain pen which is so constructed as to allow air to leave the pen barrel under certain conditions, but in which the outer air is substantially prevented from entering the barrel.

A further object of the invention is the provision of a fountain pen adapted to be filled by ink under pressure which will permit escape of air, but prevent the escape of liquid.

A still further object of this invention is the provision of a fountain pen adapted to be filled by ink under pressure whereby no vacuum is created above the ink in the barrel.

These and other objects will be apparent to one skilled in the art from a study of the following description and accompanying drawing in which

Figure 1 is a longitudinal sectional view through the upper portion of a fountain pen showing one form of the present invention;

Fig. 2 is a sectional view similar to Fig. 1, but showing a modification thereof;

Fig. 3 is a sectional view showing a still further modification;

Fig. 4 is a sectional view similar to the preceding figures, but showing a still further modification;

Fig. 5 is a view of the pressure responsive valve of Fig. 2, the view being taken on line 5—5, Fig. 2;

Fig. 6 is a fragmentary detail of the valve shown in Figs. 2 and 5, the valve being in open position;

Fig. 7 is a sectional view taken on line 7—7 of Fig. 3; and

Fig. 8 is a sectional view taken on line 8—8 of Fig. 4.

Referring now to the drawing in detail, the pen is shown with the usual barrel A, writing portion B, and valve control means C. In Fig. 1 the upper end portion of the barrel is internally threaded at 2 for securing a cap or end closure 4, the interior of which is provided with a bore 6 in which is fitted the cylindrical stem 8 of a vent member 10, suitably formed to seat on a shoulder 12 formed in the upper portion of the barrel. The end closure member 4 bears against the vent

member 10 to seal the latter with respect to the barrel. The stem 8 of the vent member 10 does not completely fill the bore 6, but is formed to provide a space constituting a valve chamber 7 in which is positioned a valve 14 retained by spring 16 to normally close the upper end of a bore 18 which extends through the vent member 10 and through a tube 20 depending therefrom and provided at its lower end portion with a valve chamber 24 in which is seated a ball check valve 22 retained by a pin or other suitable means 26. Formed in the cap member 4 and extending from valve chamber 7 to the atmosphere is an air duct 28.

In the form of the invention shown in Figs. 2, 5 and 6 the upper portion of the barrel A is closed by means of a vent member in the form of a valve housing 30 which includes a base member 32 seated on a shoulder 34 formed in the barrel and clamped thereon by cap member 38. A cylindrical bushing 36 extends upwardly from the base member 32 and is arranged in a recess formed in the end closure or cap 38, and the bushing is formed to provide an air chamber 39, the upper end of which is closed by a valve 42 which is held in position by spring 44 placed in the valve chamber 40. An air vent 46 leads through the cap and connects the valve chamber 40 to the atmosphere. The valve housing 30 also includes a tube 48 which depends from the base member 32 and has a portion enlarged to form a holding element 50 for a flexible and elastic diaphragm 52 which is adapted to close an air port or duct 54 leading from the longitudinal bore 56 in the lower portion of the tube. The duct 54 is formed in the enlarged portion 50, which is also provided with a duct 58 which communicates with an air chamber 39 through the duct 60. The length of tube 48 and the resilience of the diaphragm 52 are so chosen and proportioned as to constitute a pressure responsive valve, the operation of which will be more fully described.

The form of the invention shown in Figs. 3 and 7 operates in exactly the same manner as that shown in Fig. 2, but the parts have been arranged differently. In this form the barrel A is provided with an internal shoulder 62 which supports a multi-part valve member C comprising a base member 64 from which a tube 66 of suitable length depends, the tube has a longitudinal bore 68 which communicates with an inclined axially extending bore 70 formed in the base member 64. A central depression 72 is formed in the upper portion of the base member and is

in direct communication with the interior of the barrel through a plurality of relatively large apertures 74. In effect the valve member 64 is substantially wheel-shaped in plan, depression 72 being formed in the hub portion and the apertures 74 being defined between what may be termed spokes, the latter being connected by a rim seated on shoulder 62 of the barrel, and with the bore 70 extending through one of the so-called 10 spokes. The depression 72 is covered by an elastic diaphragm 76 covering the lower valve member 64 and the diaphragm is flanged at 78, which flange is received in a recess in the rim of base member 64 and is held in place by the upper valve member 80. An air port 82 is provided in the diaphragm to connect duct 70 and duct 84, the latter duct being formed in the upper valve member and having one end in communication with recess 86 formed in the lower surface of the upper 20 valve member and covered by the before-mentioned diaphragm. The upper valve member 80 also includes a cylindrical bushing 88 arranged within a recess formed in the cap 90 having threaded engagement with the barrel to retain 25 the valve members and diaphragm in assembled relation. The bushing 88 does not completely fill the cap recess in order to provide a valve chamber 92 in which is a valve 94 urged by spring 96 into sealing engagement with the upper end 30 of the bushing to close and seal the air chamber 89 against ingress of air. The chamber 89 is in communication with recess 86 through port 98, while valve chamber 92 is vented to atmosphere by bore 100.

35 In the form of the invention shown in Figs. 4 and 8 the barrel A supports at its upper end a vent member 101 which is threaded into a cap or end member 103 which is in turn threaded onto the barrel as shown at 105. The 40 vent member 101 comprises a supporting portion 107 which rests on the upper end of the barrel A and is formed with a head 109 with which an elastic diaphragm 111, formed of rubber or the like, is grippingly engaged as shown at 113. Depending from the supporting portion 107 of vent member 101 is an outer tube 115 provided with a reduced lower end portion 117, substantially nozzle-shaped and having a port 119 therethrough which communicates with the interior or bore 121 50 of said tube. The bore 121 extends entirely through the vent member 101 and has an inner tube 123 arranged therein, said inner tube providing a longitudinal bore 139. The tube 123 at its upper end portion is of a diameter such as to 55 snugly fit within the bore 121 whereby said inner tube is held in position as shown at 125, while the lower end portion of the tube 123 is reduced in diameter and concentrically arranged within the outer tube 115 whereby to provide an air 60 space 141 between the inner and outer tubes as clearly shown in Fig. 4. The upper end portion 125 of the inner tube 123 is provided with a plurality of longitudinal air ports 127 therethrough which connect the air space 141 with the space 65 between the diaphragm 111 and the upper end portion of the vent member 101. The inner tube 123 is provided at its upper end portion with a tapered valve seat 129 in which is positioned a ball check valve 131 adapted under certain conditions to close a port 133 formed in the diaphragm 111 and the cap 103 is provided with a recess 135 in which the head 109 of vent member 101, and the diaphragm 111, are arranged. A duct 137 extends through the cap 103 to the atmosphere to vent air from the recess 135.

Each of the pens described are intended to be filled by ink under pressure, the pressure being supplied by means such as disclosed in Patent 2,011,639, granted August 20, 1935, and of which the present case is a division. 5

Assuming ink under pressure is supplied to the pen shown in Fig. 1, the ink will enter the barrel, compressing the air above the ink until sufficient pressure is reached to unseat the check valve 14 which will permit escape of the trapped air to 10 the atmosphere through duct 28, following which the valve will reseat and the operation repeated until such time as the ink within the barrel reaches the level of valve 22. This valve 22 is 15 buoyant and when the air reaches the same it will rise and close the bore 18, thus preventing the egress of any further air and limiting the inflow of ink. Further ink may flow into the barrel by compressing the trapped air but this excess ink will be rejected upon removal of the external 20 pressure due to the expansion of the trapped air.

In the form shown in Fig. 2 as ink is forced into the barrel the air tends to be compressed but, since diaphragm 52 is normally in a position approximating that shown in Fig. 6, the air can 25 escape through bores 56, 54, 58, 60, chamber 39, check valve 42 and bore 46 to the atmosphere. As soon as the ink reaches the lower end of tube 48 it closes bore 56 and no more air can escape from the barrel, this causes the ink to rise in the 30 bore 56, which rise will necessarily compress the trapped air, and since the rising column of ink forms but a small part of the volume of chamber 39 a difference of pressure is established on opposite sides of the diaphragm. The pressure of 35 trapped air acting on the large area of the diaphragm 52 will force it against the port 54 thus sealing this port and preventing the escape of any ink from the pen. It is thus seen that a pressure controlled valve is provided which, due to the 40 unbalanced pressures arising when the ink closes the lower portion of the escape tube, will operate to prevent the egress of air or ink from the barrel. As soon as the pressure is removed from the pen the trapped air expands and forces the excess ink 45 out of the pen.

The form shown in Fig. 3, as previously stated, operates by unbalanced pressures exactly as does that form just described. In this form air can escape through bores 68, 70, port 82, bore 84, recess 86, bore 98, chamber 89, check valve 94 and bore 100 to the atmosphere. The diaphragm 76 is thus, as was diaphragm 52, subjected to equal pressures on both sides until such time as the ink closes the tube 66, at which time the air in the barrel will be compressed and acting on the lower side of the diaphragm will effectively seal the bore 84 against escape of air or ink from the pen barrel. The application of further pressure tends to further compress the trapped air and still more effectively seal the escape port, which trapped air will expand upon removal of the external pressure and cause the excess ink to pass out of the pen.

In the form of the invention shown in Figs. 4 65 and 8 it can be seen that normally the port 133 in the diaphragm 111 is closed by the ball valve 131. It can also be seen that with the parts in their normal position as shown in Fig. 4 the ball valve 131 closes port 133 against escape of air 70 therethrough. The specific arrangement shown in Fig. 8 provides three columns of air; one within the barrel A, another indicated at 141 around the tube 123, and a third, the bore 139 of the inner tube 123 and these columns are normally 75

at a uniform pressure. This condition prevails as long as communication exists between them and the interior of the barrel at the lower end of tube 123 by means of the port or opening 119 in the nozzle portion 117 of tube 115. As ink enters the barrel A, the air in these three columns is compressed; the air in column 141 passing through ports 127. When sufficient pressure has developed beneath the diaphragm 111, the latter will be deflected to uncover port 133 to permit escape of air through said port to the atmosphere through vent 137. As long as the ink level remains below the nozzle 117, the valve 131 will remain seated to close the upper end of bore 139. When, however, the ink reaches the lower end of the nozzle 117 as shown by the ink level indicated in dotted lines at 143, the lower end of the nozzle 117 is closed and air communication between the interior of the barrel A and the vent member is severed. Increase of ink in the barrel A to the level diagrammatically indicated by a broken line at 145 establishes three independent columns of air, the pressure of which will increase at the same ratio as ink continues to be forced into the barrel A. This increasing air pressure will become sufficient to deflect diaphragm 111 to allow air to escape through the port 133 from the column 141, causing the air pressure in the same to decrease and the ball valve 131 to be lifted from its seat 129 by the higher pressure in air column 139 to close port 133 in diaphragm 111 thereby preventing further air-escape. Immediately after the closing of port 133 by ball valve 131 the pressure of the air columns 139 and 141 again will increase due to ink being pressed into bores 139 and 121 by the higher pressure of the air above the ink in the barrel A outside of tube 115. It will be apparent, therefore, that the air pressure in columns 139 and 141 will retain the ball valve 131 in its elevated position closing port 133 in the deflected diaphragm. It is apparent that above described movements of diaphragm 111 and valve 131 and changes in air pressures and ink levels will occur in immediate succession and in effect almost simultaneously. As the ink continues to be forced into the pen barrel the air above the ink becomes further compressed until a maximum quantity of ink has been admitted into the barrel. Expansion of the air within the barrel against the ink causes a reversal of flow of the ink out of the pen barrel until the ink level has receded to its normal which is somewhat below the nozzle 117. The ball valve 131 will drop to its seat 129 and the diaphragm 111 will assume its normal position as soon as the air pressure within the vent member 101 has dropped sufficiently due to the lowering of the ink level in the pen and within the columns 139 and 141. From the description of the pens and the operation thereof it is seen that a pressure filled pen is provided which will be effectively filled to a certain level due to the escape of air, but cannot be filled and retain ink beyond this level after the pen has been removed from the source of filling pressure. It will be obvious to one skilled in the art that the filling of the pen under pressure and the expansion of the trapped air tend to keep the passages at the writing tip free and unobstructed due to the flushing action of the ink under pressure.

It will be obvious to one skilled in the art that the drawing and description are purely illustrative and are not intended to limit the invention, and that further modifications and improvements

are possible without departing from the scope of the invention as defined by the appended claims.

What is claimed is:

1. In a fountain pen having a barrel, an air vent member in the barrel, a hollow cap secured to the barrel and securing the air vent member in position, said air vent member including a stem having a bore therethrough leading to the interior of the cap, a valve normally closing said vent member against passage of air to the interior of the cap but operative to establish communication between the barrel and cap upon increase in air pressure in the bore of the stem beyond a predetermined amount, a duct leading from the interior of the cap to the atmosphere, and valve means associated with the air vent member and operative in response to variations in level of the ink in the pen barrel to close said air vent member against passage of air therethrough.

2. In a fountain pen, a barrel having a recessed cap closing the upper end thereof, air vent means secured within the barrel by said cap and so formed as to provide an air chamber in its upper portion, a valve normally closing the air chamber, said vent means including air ducts in communication with the air chamber, a diaphragm associated with the air vent means in such a manner as to be deflected by air within the barrel when said air is at a pressure in excess of the air within the air ducts to close the air vent means and prevent passage of air to the air chamber.

3. In a fountain pen, a barrel, a cap closing one end of said barrel, air vent means in the barrel and secured by said cap, a duct in the cap for discharging air from the vent means outside the pen, a valve normally preventing escape of air from the vent means to the duct but operative in response to air pressure beyond a predetermined amount to vent air to said duct, and a second valve associated with the vent means operative in response to variations in ink level in the pen to close said vent means against passage of air therethrough.

4. A fountain pen comprising a barrel, a cap closing the upper end of the barrel and provided with an internal valve chamber and a duct leading therefrom through the cap, air vent means within the barrel secured by the cap and through which air is expelled upon entrance of ink into the barrel, a valve in the valve chamber normally closing the vent means against escape of air to the valve chamber but operative upon increase in air pressure in the vent means to permit escape of air, said vent means being so formed and arranged as to receive ink when the latter reaches a predetermined level in the barrel whereby to prevent further escape of air from the barrel through the vent means and to control the admission of ink to the barrel.

5. In a fountain pen adapted to be filled by liquid under pressure, a liquid containing barrel, a cap closing the upper end of the barrel, a chamber within the cap having communication with the atmosphere, control means within the barrel comprising, valve means permitting escape of air from the barrel while preventing entrance of air to the barrel, and additional valve means operative upon the liquid reaching a predetermined level to prevent further escape of air, thereby checking the further entrance of liquid to the barrel.

6. In a fountain pen adapted to be filled by liquid under pressure, a liquid containing barrel,

control means within the barrel adapted to permit entrance of liquid into the barrel and the escape of air from the barrel, at least a part of said means operating automatically to prevent entrance of air to the barrel whereby a predetermined amount of liquid will be maintained within the barrel.

7. In a fountain pen adapted to be filled by liquid under pressure, a liquid containing barrel, control means within the barrel comprising, one way valve means automatically operating to prevent entrance of air to the barrel while permitting escape of air from the barrel, and buoyant means actuated by the liquid to prevent further escape of air.

8. In a fountain pen adapted to be filled by liquid under pressure, a liquid containing barrel, a cap, control means within the barrel and cap comprising, one way valve means permitting the escape of air from the barrel, and diaphragm means responsive to unbalanced air pressures to prevent further escape of air through said valve means.

9. In a fountain pen adapted to be filled by liquid under pressure, a liquid containing barrel, a cap, control means within the barrel and cap comprising, one way valve means permitting the escape of air from the barrel, and diaphragm means operative in response to unbalanced air pressure arising upon the liquid reaching a predetermined level to prevent further escape of air through said means.

10. In a fountain pen adapted to be filled by liquid under pressure, a liquid containing barrel, a cap closing the upper end of the barrel and having an air vent therethrough, control means within the barrel comprising, valve means permitting escape of air from the barrel through the air vent while preventing entrance of air to the barrel, and additional valve means operative upon the liquid reaching a predetermined level to prevent further escape of air.

11. In a fountain pen adapted to be filled by

liquid under pressure, a liquid containing barrel, a cap closing the upper end of the barrel and having an air vent therethrough, control means within the barrel comprising, valve means permitting escape of air from the barrel through the air vent while preventing entrance of air to the barrel, duct means extending lengthwise of the barrel a predetermined distance, and additional valve means interposed in said duct normally permitting the flow of air therethrough, said additional valve means being operative to close the duct upon the liquid level reaching the lower end of said duct.

12. In a fountain pen adapted to be filled by liquid under pressure, a liquid containing barrel, a cap closing the upper end of the barrel and having an air vent therethrough, control means within the barrel comprising, valve means permitting escape of air from the barrel through the air vent while preventing entrance of air to the barrel, duct means extending lengthwise of the barrel a predetermined distance, and a diaphragm valve interposed in said duct and normally permitting the flow of air therethrough, said diaphragm valve deflecting to close the duct upon the liquid level reaching the lower end of said duct.

13. In a fountain pen adapted to be filled by liquid under pressure, a liquid containing barrel, a cap closing the upper end of the barrel and having an air vent therethrough, control means within the barrel comprising, valve means permitting escape of air from the barrel through the air vent while preventing entrance of air to the barrel, duct means extending lengthwise of the barrel a predetermined distance, and diaphragm valve means interposed intermediate the ends of said duct and normally permitting the flow of air therethrough, said diaphragm valve means deflecting to close the duct upon establishment of unequal pressures due to the liquid level reaching the lower end of said duct.

KARL Y. JOHANNESSON.
